Primary Examiner — George A Bugg*Assistant Examiner* — Tamara L Hahn(74) *Attorney, Agent, or Firm* — Steven Rinehart(57) **CLAIM**

The ornamental design for a cantilever rack with backset braces, as shown and described.

DESCRIPTION

FIG. 1 is a perspective view of a cantilever rack with backset braces;

FIG. 2 is a perspective view thereof; shown in use with environment.

FIG. 3 is a front end view thereof;

FIG. 4 is a left side view thereof;

FIG. 5 is a right side view thereof;

FIG. 6 is a top plan view thereof; and,

FIG. 7 is a rear-end view.

The broken lines in the drawings are for the purpose of illustrating the environment of a cantilever rack with backset braces only and form no part of the claimed design.
